LINDSLEY SCHEPMOES, OF HASBROUCK HEIGHTS, NEW JERSEY, ASSIGNOR TO SAFETY CAR HEATING & LIGHTING COMPANY, A CORPORATION OF NEW JERSEY.

LAMP.

1,131,428.

Specification of Letters Patent.

Patented Mar. 9, 1915.

Application filed May 21, 1912. Serial No. 888,726.

To all whom it may concern:

Be it known that I, LINDSLEY SCHEPMOES, a citizen of the United States, residing in Hasbrouck Heights, county of Bergen, and State of New Jersey, have invented new and useful Improvements in Lamps, of which the following is a description.

My invention pertains to that class of lamps wherein it is desired to support a source of illumination and direct the rays thereof in a predetermined manner.

As my invention is particularly applicable to lamps adapted to be supported from a ceiling or deck and cast most of their rays in a downward direction over considerable area, it will be described with respect to such a lamp.

In the drawing, Figure 1 represents a vertical section and partial elevation of one form of lamp embodying my invention. Fig. 2 is a top plan of a bowl supporting member used in the type of lamp shown in Fig. 1. Fig. 3 is an elevation of the bowl supporting member shown in Fig. 2. Fig. 4 shows a portion of the bowl supporting member shown in Figs. 2 and 3 and an elevation of a hinge employed in my lamp. Fig. 5 shows a portion of the bowl supporting member shown in Figs. 2 and 3 and an elevation of a latch employed in my lamp.

In the drawing, referring particularly to Fig. 1, 1 represents a supporting spider comprehending an annular ring which may be secured in proper position against the deck or ceiling 2 as by means of bolts 3. The said supporting member or spider is provided with a plurality of legs 4 uniting the ring portion with the central threaded portion 5 into which is screwed the nipple 6 which may be held firmly in place as by lock nuts 7. The nipple 6 carries the socket 8 adapted to properly support an electric lamp or bulb 9 which may readily be wired as indicated in the figure. 10 represents an ornamental shell or inclosing member covering the spider, nipple and socket and is attached to the spider or supporting member as by means of screws 11. The shell 10 is provided with a threaded portion 12 upon which is made up the threaded member 13 provided with an internal conical surface 14 adapted to crowd the flexible fingers 15 inwardly as the member 13 is moved downwardly. The fingers 15 are preferably united at their upper ends to form an annular

ring portion which is attached to the member 12 as by means of screws 16. The said fingers 15 are so shaped at their lower extremities that when they are pressed inwardly by the member 13 they will engage 60 the flange or neck of a shade or reflector 17 and hold the same in a proper position.

The bowl supporting member or spider, comprising the annular portion 18 shown in Figs. 1, 2 and 3 and provided with depressions 19 to accommodate the heads of the screws 16, is attached to the member 10 as by means of screws 20. The said spider comprises a plurality of legs 21 supporting the annular ring 22, provided with a boss 23 70 which together with two ears or lugs 24, shown in Fig. 4, cooperates with a pin 31 as indicated in the said figure to form a hinge. The said bosses 24 are united as by rivets to a split ring 25 of sheet metal of substantially U-shaped section. The ends of the split ring are both attached to suitable lugs 26 which may be drawn toward each other as by means of the screw 27, shown in Fig. 5, which screw engages the latch 28 so as to 80 hold the ring in proper position as indicated in Fig. 1. By removing the screw 27, the ring may be opened to receive the lip or flange of a suitable bowl 30 having its lip preferably covered for a portion thereof 85 with an elastic material 29, and when the ends of the ring 25 are brought toward each other and the screw 27 made up the said screw will firmly hold the bowl 30 in proper 90 position within the ring 25.

In placing my lamp in service I prefer to proceed in the following manner: The nipple 6 is first made up in the portion 5 of the supporting member 1 and firmly clamped in place as by means of the lock nuts 7. The socket 8 is wired and then made up upon the nipple 6 as shown in Fig. 1. The wires may then be coupled up with an external circuit in a well known manner. The supporting member 1 is then firmly made fast to the deck or ceiling as by means of the bolts or screws 3 and when in proper position I pass the shell 10, having the members 13 and 15 properly in place thereupon, over the socket and nipple and into the position shown in Fig. 1, in which position it may be firmly held by inserting and making up the screws 11. I then press the neck or flange of the shade 17 into the fingers 15 and revolve the member 13 in such manner as to move 100 the member 13 in such manner as to move 105 the member 13 in such manner as to move 110

the same downwardly and through the instrumentality of the internal conical bore 14, the members 15 are crowded into the recess in the neck or flange of the shade or reflector 17 in such manner as to hold the shade firmly in its proper position. I then place the bowl supporting spider with its ring 18 in proper position against the lower portion of the member 10 and insert the screws 20 which hold the said spider firmly in its proper relative position with respect to said member 10. By withdrawing the screw 27 the ring 25 may be opened and the lip of the bowl 30 inserted within the ring and then by replacing 15 the screw 27 and making up the same the bowl 30 will be held firmly within the ring. The ring may then be placed in position with the members 24 on opposite sides of the lug 23 and the pin 31 inserted through the said 20 members and the lug to cause the hinge to be properly assembled. Then if the bowl is swung into the position shown in Fig. 1, the latch or spring 28 will engage the screw 27 as shown in Figs. 1 and 5 and firmly hold 25 the bowl in place. The bowl 30 and shade or reflector 17 may be of any desired materials and in practice I prefer to make both these members of a translucent reflecting material which will allow a portion of the rays from 30 the lamp 9 to pass through the same but will reflect most of the rays for the following purpose: By making the shade or reflector 17 of a translucent or semi-transparent material, most of the rays falling upon the inner surface of the said member 17 are reflected downwardly more or less in a cone of large divergence so as to light a considerable area. However, a portion of the rays, by 35 passing through the material of the reflector 17, will serve to light the deck or ceiling sufficiently to make the same attractive. The bowl 30, if made of translucent material, will screen the source of illumination or bulb 9 sufficiently that, if looked at directly by an 40 observer, no discomfort, due to intensity of light, will be experienced and the rays reflected by the bowl 30 will, by striking the reflector 17, be reflected over considerable area as well as the direct 45 rays from the bulb 9. Therefore, it will be noted that my invention produces a lamp which may be used for lighting in accordance with the now well known practice termed "indirect illumination."

50 I do not wish in any way to limit myself to the exact details of construction set forth in this specification which is given to illustrate one type of lamp comprehending my invention, for it will be obvious that wide 55 departure in the way of details may be made without departing from the spirit and scope of my invention which is as set forth in the following claims.

I claim—

65 1. A lamp comprehending a supporting

member; a source of illumination supported thereby; a shell carried by said supporting member and completely covering the latter; means carried directly by said shell for holding a shade; a shade carried thereby in operative relation to said source of illumination; and separate means also carried directly by said shell for supporting a bowl in operative relation to said source of illumination and below said shade. 70

2. A lamp comprehending a supporting member; a source of illumination carried thereby; a shell completely covering said supporting member; shade supporting means carried directly by said shell; a shade 80 carried by said means; separate means also carried directly by said shell for supporting a bowl in operative relation to said source of illumination; and a bowl carried by said latter means. 85

3. A lamp comprehending a supporting member; a source of illumination carried thereby; a shell completely covering said supporting member; shade supporting means carried by said shell at its lower end; 90 and bowl supporting means also carried by said shell and extending below the shade supporting means.

4. A lamp comprising a supporting member; a shell covering said member and having shade supporting means at its lower end; a shade carried by said means; means for carrying a bowl also carried by the lower end of said shell and extending from within downwardly below said shade supporting 100 means; and a bowl carried by said means, whereby the shade and bowl are supported one above the other. 95

5. A lamp comprehending a supporting member; a source of illumination carried thereby; a shell covering said member and having a shade for directing rays emitted by said source of illumination; and a bowl also carried by said shell spaced a material distance from the shade to intercept direct 110 rays of said source of illumination, transmit a portion of said rays, and reflect a portion of said rays upon said shade. 110

6. A lamp comprising a supporting member carrying a source of illumination; an ornamental shell inclosing the supporting member and having at its lower end shade holding means; bowl supporting means separately carried by the lower end of the shell and projecting downwardly below the shade 120 supporting means; a shade carried by the shade supporting means; a bowl carried by the bowl supporting means; and means whereby the bowl may be swung downwardly upon the bowl supporting means to obtain access to the source of illumination. 125

7. A lamp comprising a supporting member carrying a source of illumination; a shell covering said supporting means and having at its lower end shade supporting 130

means arranged adjacent the source of illumination; a shade secured to the shade supporting means above the source of illumination; bowl supporting means carried by the lower end of the shell and extending within the shade and below the same; and a bowl carried by the bowl supporting means so as to cover the bottom of the source of illumination, the arrangement of the bowl and shade being such as to, between them, encompass the source of illumination.

8. A lamp comprising a supporting member carrying a source of illumination depending therefrom; a shell carried by the supporting member; means at the lower end of the shell for engaging and supporting a shade; means movable on the shell for co-operation with the shade supporting means; and bowl supporting means also secured to the lower end of the shell and extending downwardly within the shade supporting means to a point near the bottom of the source of illumination, said bowl supporting means having a hinged bowl carrying member.

9. A lamp comprising a supporting member; a source of illumination carried thereby; a shell carried by said member and entirely covering the latter; means fixedly se-

cured to the end of the shell for holding the shade; and means movably mounted on said shell for covering said last-named means.

10. A lamp comprising a supporting member; a source of illumination supported thereby; a shell carried by said member and covering the latter; means comprising a plurality of resilient fingers having overturned outer ends for engaging and holding a shade adjacent said source secured to said shell; and means comprising a plurality of legs secured to said shell and extending downwardly below said fingers to support a bowl adjacent said source of illumination.

11. A lamp comprising a supporting member carrying a source of illumination depending therefrom; a shell carried by the supporting member; means at the lower end of the shell for engaging and supporting a shade; means movable on the shell to co-operate with the shade-supporting means to cover the same; and means also secured to the shell and extending downwardly to support a bowl below said source.

LINDSLEY SCHEPMOES.
